Primary Examiner — Cynthia M. Chin

(74) Attorney, Agent, or Firm — McDermott Will & Emery LLP

(57) **CLAIM**

We claim the ornamental design for a rocket, as shown and described.

DESCRIPTION

FIG. 1 is a top perspective view of a rocket according to the new design.

FIG. 2 is a bottom perspective view of the rocket shown in FIG. 1.

FIG. 3 is a right side view of the rocket shown in FIG. 1.

FIG. 4 is a left side view of the rocket shown in FIG. 1.

FIG. 5 is a front view of the rocket shown in FIG. 1.

FIG. 6 is a rear view of the rocket shown in FIG. 1.

FIG. 7 is a top plan view of the rocket shown in FIG. 1; and, FIG. 8 is a bottom plan view of the rocket shown in FIG. 1. The broken lines are for the purpose of illustrating portions of the rocket that form no part of the claim.
